(57) **CLAIM**

The ornamental design for an insulated container, as shown and described.

DESCRIPTION

FIG. 1 is a side perspective view of an embodiment of our new insulated container;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a side perspective view of an alternate embodiment of our new insulated container;

FIG. 8 is a left side elevation view thereof;

FIG. 9 is a right side elevation view thereof;

FIG. 10 is a front elevation view thereof;

FIG. 11 is a rear elevation view thereof; and,

FIG. 12 is a top plan view thereof.

The broken line showing is for illustrative purposes only and forms no part of the claimed design.
